UNITED STATES PATENT OFFICE

118,514

DESIGN FOR A PORTABLE HEATER

Clifford Brooks Stevens, Milwaukee, Wis., assignor to Cleaver-Brooks Company, Milwaukee, Wis., a corporation of Wisconsin

Application July 26, 1939, Serial No. 86,260

Term of patent 7 years

To all whom it may concern:

Be it known that I, Clifford Brooks Stevens, a citizen of the United States, residing at Milwaukee, in the county of Milwaukee and State of Wisconsin, have invented a new, original, and ornamental Design for a Portable Heater, of which the following is a specification, reference being had to the accompanying drawing, forming part thereof.

In the drawing:

Fig. 1 is a side elevational view of a portable heater showing my new design.

Fig. 2 is a top plan view thereof.

Fig. 3 is a rear elevational view thereof.

The front of the body portion has a plain enclosure.

I claim:

The ornamental design for a portable heater, as shown and described.

CLIFFORD BROOKS STEVENS.
